UNITED STATES PATENT OFFICE.

ALBERT SHANNON YORKS, OF NESHANIC STATION, NEW JERSEY.

POCKET TOILET SET.

No. 909,273.

Specification of Letters Patent.

Patented Jan. 12, 1909.

Application filed May 13, 1908. Serial No. 432,722.

To all whom it may concern:

Be it known that I, ALBERT S. YORKS, a citizen of the United States, residing at Neshanic Station, in the county of Somerset and State of New Jersey, have invented a new and useful Pocket Toilet Set, of which the following is a specification.

This invention relates to a toilet article.

The object of the invention is to provide an article of this character that shall combine, in neat and compact form, a hair and clothes brush, the two brushes being separate and distinct, and being normally housed within the handle of the brush but adapted, when required for use, to be projected beyond the handle and in position for application.

With the above and other objects in view, as will appear as the nature of the invention is better understood, the same consists, generally stated, in a toilet article embodying a handle, a plurality of brush members held for pivotal movement within the handle, and means for projecting the members beyond the handle and for locking them in this position while being used.

The invention consists further in the various novel details of construction and combination of parts of a combined clothes and hair brush, as will be hereinafter fully described and claimed.

In the accompanying drawings forming a part of this specification, and in which like characters of reference indicate corresponding parts, Figure 1 is a view in perspective of the article, showing the two covers thereof partly removed, one for the purpose of exhibiting a brush section and a pocket comb, and the other for the purpose of exhibiting a mirror. Fig. 2 is a vertical longitudinal sectional view of the brush. Fig. 3 is a top plan view, partly in section, showing the brush sections or members in their folded position. Fig. 4 is a view in plan, partly in section, of a modified form of brush. Fig. 5 is a transverse sectional view through the implement shown in Fig. 4.

The article shown in Figs. 1, 2 and 3, comprises a handle 1 and two covers 2 and 3 having a sliding engagement therewith, the connection between the parts being secured in this instance by providing the covers with

inturned tongues 4 that engage with grooves 5 in the sides of the handle adjacent to each edge. The handle may be made of any suitable material, such as wood, or of metal, such as aluminum, and the covers will, by preference, be made of the same material as the handle. As shown in Fig. 3, the handle is approximately rectangular in form, its corners being preferably rounded, as are also the corners of the covers, in order to prevent wear of the pocket in which the article is carried.

Arranged within the handle, midway of the width of the sides thereof, and secured to the ends of the handle, is a partition 6 which, as shown in Fig. 3, is of less width than the interior of the handle. On the opposite sides of the partition are mounted the brush members or sections, each of which consists of a split metallic tube 7 and a plurality of tufts 8 of hair, bristles, or other suitable substance. The tufts are held within the tube by employing a suitable cement, such as shellac or the like, and are of such length that when opened out or projected beyond the plane of the handle, as shown in Fig. 2, the series of brush members will be in position for use. It is desired that the brush members on one side of the partition shall be used for smoothing the hair, while those on the other side will be employed for brushing clothes. The two series of tubes 7 are held assembled with the partition 6, for rotary movement relatively thereto, by keepers 9, which in this instance are formed from lengths of wire sufficiently long to pass around the tubes of the two series, the wires being inserted through openings provided in the partitions for the purpose. While this mode of connecting the tubes with the partition will be found thoroughly efficient for the purpose designed, yet it is to be understood that the invention is not to be limited thereto, as any other arrangement suited to the purpose may be employed. Connected with one end of each of the tubes of both series is an arm 10, the arms on the two series of tubes being arranged at opposite ends, so that there will be no interference in the operation of the mechanism for raising and lowering the brush members. Each of these arms of one series

is pivotally connected with a rod or bar 11, and each of the arms of the other series is pivotally connected with a similar rod or bar 12, and connected with each of the push rods 5 11 and 12 is a push button 13 and 14, respectively, the connection between the push buttons and the push rods being secured by means of shanks 15, slots 16 being provided in the sides to receive the shanks of the push 10 buttons. It will be seen from this arrangement that when a push button is moved in the proper direction, all of the brush members of one of the brushes will be raised, and when pushed in the opposite direction, all of the 15 brush members will be forced into the handle, with the tufts lying one upon the other in the successive series, as shown in Fig. 3.

As will be obvious, it will be necessary to lock the brush members in their projected 20 position, otherwise the article will lack utility. To accomplish this result, a pair of leaf springs 17 is provided, one being arranged at each corner of one end of the handle, and each is provided with an inturned terminal 17^a. 25 Each of the springs is furnished with an orifice to be engaged by a pin 18, the two pins being carried by the buttons 13 and 14, as shown in Fig. 3. The function of the inturned terminals 17^a is to present cam surfaces upon 30 which the pin will ride when approaching the orifice in the spring. In order to permit the springs 17 to be moved inward a sufficient distance to clear the pins 18, the partition is provided with notches 19, one only being 35 shown, to receive the curved terminals. The springs are flexed to free them from engagement with the pins by push buttons 20 that project through openings in the sides of the handle provided for the purpose. In 40 order to increase the utility of the device, one of the covers has a mirror 21 connected with it, and a comb 22 is provided which will occupy either of the spaces between the brushes and the inner sides of the covers.

45 In the form of the invention shown in Figs. 4 and 5, the sides 23 of the handle are turned inwardly toward each other to form four flanges 24, and between these flanges are secured in any preferred manner, two partitions 50 25 and 26. The partitions will be secured to the flanges in any preferred manner, preferably by being soldered thereto, but as will be apparent when the handle is made of wood these partitions will be glued in position. The intermediate portion of each of 55 these partitions is provided with a longitudinal groove 27 in which is fitted the horizontal partition 28.

Extending through suitable openings provided in the partitions for the purpose are the metallic tubes 29 that carry the tufts of hair 30 constituting the brushes, it being understood, as shown in Fig. 1, that the tubes are disposed on opposite sides of the parti-

tion 28. To hold the tubes in position one end of each of the tubes on one side of the partition is outwardly flared, as shown at 30, the opposite end of each of the tubes on the other side of the partition being similarly treated. Secured to the plain ends of the tubes, or those opposite the flared portions, are arms 10 that are secured to the push rods 11 and 12 in the same manner as that shown in Fig. 1 and which operate to raise and lower the two sets of brushes in the manner first 75 described. The other parts of the brush shown in Figs. 4 and 5 are similar to those shown in Figs. 1, 2 and 3, and therefore need no detailed description.

By the provision of the partitions 26, the arms 10 and push rods 11 and 12 are housed in such manner as to be protected from the deteriorating effects of moisture so that the operation of the brush may be assured for an 80 extended period.

85 From the foregoing description, it will be seen that the improvements herein defined, while simple in character, will be thoroughly efficient for the purposes designed, and will coöperate in the production of a useful toilet 90 article.

What is claimed is:—

1. A brush comprising a handle, a partition arranged therein, brush members arranged on each side of the partition, an arm projecting from each of the brush members, a rod pivotally connected with each series of arms to rock the brush members, a push button connected with each of the rods and projecting beyond opposite sides of the casing, and locking means coacting with the buttons to hold the brush members in projected position.

105 2. A brush comprising a handle, a partition arranged therein, brush members located on each side of the partition, an arm projecting from each of the brush members, a rod pivotally connected with each series of arms to rock the brush members, a push button connected with each of the rods and projecting beyond opposite sides of the casing, an inward projecting pin carried by each push button, springs secured to the inner surfaces of the sides of the handle and provided with orifices to be engaged by the pins, and means 110 for moving the springs out of engagement with the pins.

115 3. A brush comprising a handle, a partition arranged therein, brush members located on each side of the partition and being secured for rotary movement thereto, an arm projecting from each of the brush members, a rod pivotally connected with each series of arms to rock the brush members, a push button connected with each of the rods and projecting beyond opposite sides of the casing, an inward projecting pin carried by each 120 push button, springs secured to the inner 125 surfaces of the sides of the handle and provided with orifices to be engaged by the pins, and means for moving the springs out of engagement with the pins.

sides of the opposite walls of the handle and provided with cam terminals and with orifices to be engaged by the pins, and push buttons carried by the springs and projecting beyond the opposite sides of the casing to move the springs out of engagement with the pins.

5 In testimony that I claim the foregoing as

my own, I have hereto affixed my signature in the presence of two witnesses.

ALBERT SHANNON YORKS.
